UNITED STATES PATENT OFFICE.

WILLIAM S. McLEWEE, OF YARDLEY, PENNSYLVANIA.

TELEPHONE FIRE-ALARM SYSTEM.

No. 884,607.

Specification of Letters Patent. Patented April 14, 1908.

Application filed April 9, 1908. Serial No. 310,584.

To all whom it may concern:

Be it known that I, WILLIAM S. McLEWEE, a citizen of the United States, residing at Yardley, in the county of Bucks and State of Pennsylvania, have invented certain new and useful Improvements in a Telephone Fire-Alarm System, of which the following is specification.

My invention relates to an improvement in fire alarm systems and the object of my invention is to utilize the ordinary telephone systems, now extensively in use, by providing an attachment to be placed at the subscribers end of the telephone circuit, by the operation of which attachment a distinctive signal will be produced at the central telephone station or exchange indicating to the telephone operator that a fire alarm is being sent by a subscriber, designated by a certain number at the exchange.

When a subscriber sends a fire alarm over the telephone circuit the attention of the operator at the telephone exchange is instantly attracted by the fire signal, who without waiting to answer the subscriber, immediately calls the subscriber's number to the fire headquarters.

In the accompanying drawings forming part of this specification, Figure 1, is a diagrammatic view showing the subscriber's instrument, the instrument at the telephone exchange and my improved signaling instrument; Fig. 2, is a vertical section of the signaling instrument as on line 2--2 Fig. 1, drawn on a larger scale; Fig. 3, is a horizontal section as on line 3--3 Fig. 2; and Fig. 4, is a vertical sectional view as on line 4--4 Fig. 3.

Referring to the drawings A represents the subscriber's telephone instrument and B represents the telephone exchange instrument which instruments are connected by wires 1 and 2 forming the main telephone circuit. C represents the signaling instrument connected by wires 3 and 4 to the wires 1 and 2 forming said main telephone circuit. The circuit formed by the wires 3 and 4 is open when the signaling instrument C is out of use so that the main telephone circuit will operate as though the signaling device were not connected thereto.

The complete telephone system is illustrated in Fig. 1, which operates in the usual manner, described briefly as follows: By removing the receiver 5 at the subscribers sta-

tion A, the circuit will be completed, through the wires 1--2 and the hook 6, which will be energized by the battery 7 and light the lamp 8 at the exchange B, thus calling the attention of the operator, who inserts a plug 30 at the point 9 to connect the subscriber with the answering instrument or to connect the subscriber with another subscriber. When the operator desires to call a subscriber the bell 10 is rung by the circuit formed by the 65 wires 1 and 2 through the condenser 11.

My improved signaling device described in detail hereinafter, closes the telephone circuit formed by the wires 1 and 2 which lights the lamp 8 the same as when the hook 6 is 70 raised, but the signaling instrument makes and breaks the circuit in rapid succession causing a continuous flickering of the light 8 indicating to the operator that a fire alarm is 75 being sent by the subscriber.

The signaling instrument is shown in Figs. 2--3 and 4. In the casing 12 is provided bearings 13 and 14 having mounted therein a shaft 15 operated by a crank 16. Said shaft 15 carries a gear wheel 17 which meshes with 80 a smaller gear-wheel 18 mounted on a shaft 19 also mounted in the bearings 13 and 14. The shaft 19 has secured thereon a cam 20 which acts on a lever 21 which is pivoted on the shaft 22 mounted in the bearings 13 and 85 14. A spring 23 tends to hold the lever 21 in the raised position and against the terminal 24 to which the wire 3 is connected. The wire 4 is connected to the lever 21 so that when the said lever 21 contacts with the terminal 24 the circuit will be closed and light the lamp 8 at the exchange. By turning the crank 16 the cam 20 will be rotated rapidly and cause the lever 21 to vibrate, which will 90 make and break the circuit formed by the 95 wires 3 and 4 and the main telephone circuit.

The handle 25 on the crank 16 is made of heavy material so that it will normally drop to its lowest position and bring the cam 20 into the position shown in Fig. 4, which will 100 depress the lever 21 and break the contact between the lever 21 and the terminal 24 so that the main telephone circuit will not be affected when the signaling instrument is not 105 in use.

The subscriber may place the signaling instrument at any convenient location, and any desired number may be used so that a signaling instrument may be located in every room throughout the subscribers building 110

and all the instruments may be connected into one main telephone circuit.

The operation of my invention is as follows: When a fire alarm is to be given the 5 crank 16 of the signaling instrument is turned causing the lever 21 to vibrate rapidly which makes and breaks the telephone circuit causing the lamp 8 at the telephone exchange to flicker continuously as long as 10 the crank 16 is turned. As this signal is entirely different from any other that may be received at the exchange by the operator, it will be known at once that a fire alarm is being sent by a subscriber having a certain 15 number, say #112, the operator at the telephone exchange calls that number over the telephone line that goes to the fire headquarters.

It will be understood that I do not limit 20 my invention to the exact construction here shown as an electrical device may be employed for making and breaking the telephone circuit to cause a distinctive signal at the exchange, but the mechanical device is 25 more desirable as it cannot get out of order and is therefore more reliable than an electrical device.

Having thus described my invention I

claim and desire to secure by Letters Patent:—

The combination of a telephone circuit, a 30 source of current, a signal located at the telephone exchange controlled by said telephone circuit, a lever pivotally mounted at one end, said lever connected with one of the wires 35 forming the telephone circuit, a terminal connected with the opposite wire forming said telephone circuit, said lever adapted to contact with said terminal and complete said telephone circuit, a spring to act upon said 40 lever, a cam to actuate said lever against the action of said spring, a shaft on which said cam is mounted, a gear-wheel on said cam shaft, a driving shaft having a gear-wheel meshing with the said gear-wheel upon said 45 cam shaft, a crank upon said driving shaft and a weighted handle on said crank to normally stop said cam in a position in which said lever will be out of action.

In testimony whereof I affix my signature 50 in presence of two witnesses.

WILLIAM S. McLEWEE.
